UNITED STATES PATENT OFFICE

FRANK SNYDER, OF HUNTINGTON, WEST VIRGINIA, ASSIGNOR, BY MESNE ASSIGNMENTS, TO SNYDER ENGINEERING CORPORATION, OF WILMINGTON, DELAWARE, A CORPORATION OF DELAWARE

WASHING MACHINE

Application filed October 1, 1924, Serial No. 740,914. Renewed May 7, 1930.

An object of my invention is to provide a washing machine wherein a cleansing fluid is forcefully passed through the articles being washed.

5 Another object of my invention is to provide a device of the class described in which articles may be washed and rinsed without removing the articles therefrom.

Another object of my invention is to provide 10 a simple and efficient device for the purposes stated.

These and other objects are attained by the means described herein and disclosed in the accompanying drawings, in which:

15 Fig. 1 is a side elevation of a device embodying my invention, parts being broken away.

Fig. 2 is a sectional view on line 2—2 of Fig. 1.

20 Fig. 3 is a vertical section of a modified form of device embodying my invention.

Fig. 4 is a sectional view taken on line 4—4 of Fig. 3.

The tub 10 is provided with suitable legs 25 or supports 11 and 110. A suitable mounting 12 is provided for a motor 13 for driving shaft 14, carrying worm 15, operative on the worm wheel 16, and carrying crank 17. A connecting rod 18 extends upward- 30 ly from the crank 17 and has its upper end pivotally connected with a crank 19 carried by the shaft 20 extending transversely of the tub at the top thereof. From the foregoing, it will be evident that an oscillating motion is imparted to the shaft 20. At opposite ends of the shaft 20, there is 35 provided an arm, said arms 21 and 22 revolvably supporting a shaft 23 disposed within the tub 10. A cylinder 24 is fixed on the shaft 23 and is provided with a suitable door 25 that may be secured in a closed position upon the cylinder, and may also be opened for permitting access to the interior of the cylinder for depositing and removing 40 articles. The ends of the cylinder may be provided with reinforcing members 24a through which the shaft 24 extends.

Attention is called to the fact that the shape of the tub is such as to conform substantially to the arc through which the cyl-

inder is oscillated or swung. Except for the lateral extensions 26 and 27 at the sides of the tub, a relatively close fit is provided between the cylinder and the tub bottom 28 and side walls 29 and 30. The clearance between said parts of the device is approximately one fourth inch. The outer ends of the shaft 23 carry spur gears 31 and 32 that mesh with arcuate racks 33 and 34 disposed in the recesses 35 and 36 provided in the lateral extensions 26 and 27 formed at the sides of the tub. The racks 33 and 34 may be mounted upon the sides of the tub as shown at 34a in Fig. 4, or they may be bolted to the upwardly projecting extensions 37 and 38 of the legs 11 and 110. Reinforcing bars 39 and 40 may follow the contour of the lateral extensions 26 and 27 and serve as supports for the tub. The reinforcing bars may be bolted to the extensions 37 and 38 as indicated by 60.

The cylinder 24 is provided with a plurality of openings or perforations 41 through which water may enter the cylinder. The inner surface of the cylinder is provided with ribs 42 that extend toward the shaft 23 and serve as deflectors for directing fluid entering the perforations, onto and through a mass of wash within the cylinder.

The operation of my device is as follows:

An oscillating or pendular motion is imparted to the cylinder or basket 24 containing clothes to be washed. By reference to Fig. 1, it will be observed that when the basket is swung in a clock-wise direction, the basket itself will revolve with the shaft 23 in a clock-wise direction because of the engagement of the spur gears upon the arcuate racks. This movement of the cylinder serves to amass the water at the left hand end of the tub although some of the water will be finding its way through the cylinder and between the cylinder, the bottom and sides of the tub. The greater portion of water will, because it is amassed at the left hand end of the tub be forced through the cylinder, as the cylinder approaches its left hand limit of travel. This forcing of the water through the cylinder and the clothes serves to place the water under great pres-

sure, the pressure being sufficient to carry the dirt out of the interstices of the fabric of which the clothes are made. Upon the change in direction of the movement of the fabric the same action is attained at the right hand end of the tub.

A suitable drain cock 45 is provided in the bottom of the tub so that the water may be drained from the tub without removing the wash from the cylinder. In this way it is possible to first soak the clothes in cold water, whereupon this water may be drained from the tub. Hot soapy water may then be admitted to the tub. After the operator has concluded with the soapy hot water, same may be drained from the tub and rinse water run into the tub. The cylinder would be reciprocated in each of the different tubs of water enumerated, so that a thorough soaking, a thorough washing, and a thorough rinsing of the clothes is attained in the order named. This is a procedure that is of particular value in household washing machines.

Attention is called to the fact that the opposite ends of the tub are developed into chamber like structures into which the cylinder is swung. The mass of water moves before the cylinder and is impounded in the chambers and the movement of the cylinder into such water filled chambers forces the water through the cylinder and the clothes therein. The arcuate cavity in the tub, and through which the cylinder is swung is so constructed that but a little water may flow past the cylinder. The oscillating and rotating movement of the cylinder in a common direction serves to check the flow of water past the cylinder. It will be readily evident that the shaft 23 need not extend through the cylinder, and that stub shafts 23a at the ends of the cylinder, see Fig. 4 will perform the function of shaft 23. The appended claims are drawn with the intention that such stub shafts shall fall within said claims. It will also be readily evident that the tub 10a, see Fig. 4, may be elongated and the cylinder or basket be reciprocated rather than oscillated. The claims appended hereto are intended to cover such structures, although the oscillating type machine is preferable for various reasons.

What I claim is:

1. In a wash machine the combination of a tub having an arcuate bottom and substantially vertical side walls, the side walls being provided with lateral extensions for providing recesses at the sides of the tub, a perforated cylinder within the tub, having end walls and arranged for backward and forward movement, the cylinder walls being closely adjacent, but spaced sufficiently from the lower ends of the walls of the tub to permit movement of the cylinder within the tub, whereby movement of the cylinder within the tub will serve to move the greater

mass of fluid ahead of the cylinder and to minimize the flow of fluid between the cylinder and the tub so that the major portion of the fluid is impounded on a given side of the cylinder and forced through the perforations in the cylinder upon movement of the cylinder into the impounded fluid, and means within the recesses to move the cylinder backward and forward within the tub.

2. In a wash machine the combination of a tub having a substantially arcuate cavity, a shaft at the top of the tub and extending transversely thereof, an arm adjacent each end of the shaft and extending downwardly into the tub, means for oscillating the shaft, a second shaft disposed within the tub and revolvably supported by the lower ends of the arms, a perforated cylinder fixedly mounted on the second shaft, adapted to be oscillated in an arc conforming substantially to the arcuate cavity in the tub, the cylinder being closely adjacent, but spaced sufficiently from the tub to permit relative movement of the cylinder and tub, the space between the cylinder and tub being insufficient to permit an appreciable flow of fluid between the cylinder and tub, whereby movement of the cylinder causes the fluid in the tub to be moved before the cylinder and impounded in the ends of the cavity, so that further oscillation of the cylinder causes the impounded fluid to be forced through the perforated cylinder.

3. In a wash machine the combination of a tub having a substantially arcuate cavity, a shaft at the top of the tub and extending transversely thereof, an arm adjacent each end of the shaft and extending downwardly into the tub, means for oscillating the shaft, a second shaft disposed within the tub and revolvably supported by the lower ends of the arms, a perforated cylinder fixedly mounted on the second shaft, adapted to be oscillated in an arc conforming substantially to the arcuate cavity in the tub, whereby movement of the cylinder causes the fluid in the tub to be moved before the cylinder and impounded in the ends of the cavity, whereby further oscillation of the cylinder causes the impounded fluid to be forced through the perforated cylinder, a gear fixedly mounted on the second shaft, and an arcuate rack carried by the tub and engaging the gear, the rack being positioned intermediate the shafts whereby the cylinder is simultaneously rotated and oscillated in the same general direction.

4. In a washing machine the combination of a tub having an arcuate bottom and substantially vertical side walls, the side walls being provided with lateral extensions for providing recesses at the sides of the tub, a perforated rotatable cylinder within the tub, having end walls and arranged for backward and forward movement, the cylinder

walls being closely adjacent but spaced sufficiently from the lower ends of the walls of the tub to permit movement of the cylinder within the tub, whereby movement of the cylinder within the tub will serve to move the greater mass of fluid ahead of the cylinder and to minimize the flow of fluid between the cylinder and the tub so that the major portion of the fluid is impounded on a given side of the cylinder and forced through the perforations in the cylinder upon movement of the cylinder into the impounded fluid, means within the recesses to move the cylinder backward and forward within the tub, and means for positively rotating the cylinder.

5. In a wash machine the combination of a tub having end and side walls, a perforated cylinder within the tub, the walls of the cylinder being closely adjacent, but spaced sufficiently from the side walls of the tub to permit movement of the cylinder relative to the tub, the space between the walls of the tub and cylinder being insufficient to permit an appreciable flow of fluid between the said walls, whereby movement of the cylinder between the limits of the tub serves to move the major portion of the fluid content of the tub towards the ends of the tub with the cylinder and to thereby force the fluid so confined at the ends of the tub, through the perforations and the articles in the cylinder, and means for oscillating and rotating the cylinder in a clockwise direction and for alternately oscillating and rotating the cylinder in counter-clockwise direction, within the tub.

In testimony whereof, I have hereunto subscribed my name this 24th day of September, 1924.

FRANK SNYDER.
